HENRY C. KNOWLTON, OF GARDNER, MASSACHUSETTS.

Design No. 3,263, dated November 24, 1868.

DESIGN FOR A CHAIR-SEAT BOW.

The Schedule referred to in these Letters Patent and making part of the same.

To all persons to whom these presents may come:

Be it known that I, HENRY C. KNOWLTON, of Gardner, in the county of Worcester, and State of Massachusetts, have invented or produced a new and ornamental Design for a Chair-Seat Bow; and I do hereby declare the same to be fully described in the following specification, and represented in the accompanying drawings, of which—

Figure 1 is a front view or plan of such bow;

Figure 2, an end view of it;

Figures 3 and 4, transverse sections of it; and

Figure 5, a side view of it.

In its general form it is somewhat like the letter *U*. The end parts *a a* are square, or rectangular, in cross-section, the portion *b*, between the two end parts, being oval or circular in cross-section, the whole being as shown in the drawings.

I claim the said design, as represented and described.

HENRY C. KNOWLTON.
